Edward R. Palmer, Meadville, Pa., assignor to Octave Products, Inc., Meadville, Pa., a corporation of Delaware

Application April 18, 1949, Serial No. 2,097

Term of patent 3½ years

(Cl. D22—3)

To all whom it may concern:

Be it known that I, Edward R. Palmer, a citizen of the United States, residing at Meadville, in the county of Crawford and State of Pennsylvania, have invented a new, original, and ornamental Design for a Hair Trimmer, of which the following is a specification, reference being had to the accompanying drawing, forming part thereof.

Fig. 1 is a side elevational view of a hair trimmer, showing my new design,

Fig. 2 is a top plan view of the hair trimmer as shown in Fig. 1, and

Fig. 3 is an end elevational view from the left end of the hair trimmer as shown in Figs. 1 and 2.

I claim:

The ornamental design for a hair trimmer, as shown.

EDWARD R. PALMER.
